UNITED STATES PATENT OFFICE.

SAMUEL W. BARR, OF MANSFIELD, OHIO, ASSIGNOR OF ONE-HALF TO
WILLIAM H. ALBACH, OF SAME PLACE.

CASH-CARRIER.

SPECIFICATION forming part of Letters Patent No. 341,825, dated May 11, 1886.

Application filed January 4, 1886. Serial No. 187,506. (No model.)

To all whom it may concern:

Be it known that I, SAMUEL W. BARR, a citizen of the United States, residing at Mansfield, in the county of Richland and State of Ohio, have invented certain new and useful Improvements in Cash-Carriers; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of a side elevation, partly in section. Fig. 2 is a longitudinal central section; and Figs. 3 and 4 are detail views of the cash-car.

This invention has relation to vacuum cash-carriers; and it consists in the construction and novel combination of parts, as will be hereinafter set forth, and pointed out in the claims.

Referring by letter to the accompanying drawings, A designates the track-wire, which is stretched between the stations.

B is a casting, which is secured to any suitable support, and the track-wire A runs through said casting and connects the station with the cashier's desk.

D is a horizontal tube or pipe, which is connected to the casting B by a threaded connection.

E is an air-tight valve-head, which is composed of the piston-head a, packing b, and washer c, held together by the pitmen or plunger s s.

In Fig. 2, B² is a valve-head similar to the valve-head E, and to this valve-head B² a cord, T, is attached and runs over a pulley, G, journaled in a recess, H, in the under side of the casting B. At its lower end the cord T is provided with a handle, T'.

At the end of the pitman-rod s s, which project through openings in the casting B, is provided a pitman-head, I, which strikes the cash-car, which latter is held on the track-wire A in front of the casting by the spring-arms J J, projecting horizontally from the front end of each casting. These springs also receive the car when returned to the station, and serve to prevent a rebound of the car when it strikes the station.

L designates a coil or spiral spring, which encircles the plunger-rod, and returns the plunger to place after it has been projected. 55 A weighted dog, G', is pivoted to the sides of the casting B and engages the plunger-head F, and holds the latter in readiness to be projected. When the draw-rope T is pulled down quickly, the spiral spring contracts within the pipe or tube, and the valve-head B² moves forward in the tube, creating behind it what is termed a "vacuum" in the tube. When the knot or swell Z' on the draw-rope T, reaches the loop Z, the dog G is released, 65 and the valve-head E moves forward in the tube to fill the vacuum, and thus projects the plunger and drives the cash-car along the track to the cashier's desk. As soon as the draw-rope has been released the spring L expands and returns the pitman-heads to their normal positions, the weighted dog G' being operated by the plunger-head I on its return to open said dog. The weighted end H' of this dog closes the dog automatically and holds 75 the plunger ready to be again projected.

X is a U-shaped bail hinged to the dog G, and provided with a hinged arm, Y, having the loop Z, which the knot Z' strikes to release the dog. 80

Having described the invention, what I claim, and desire to secure by Letters Patent, is—

1. The combination, with the tube, and the casting having the recess with pulley therein, of the plunger-rod with plunger-heads, the air-tight valve-head secured to the rear ends of the plunger-rod, the spiral spring with valve-head B² at its rear end, the draw-rope with knot thereon, the weighted dog, and 85 the bail with hinged loops, substantially as specified.

2. The combination, with the tube and casting, of the plunger-rod with the air-tight valve-head at their rear ends, the spiral spring with valve-head B², the weighted dog with loop attached, and the knotted draw-rope, 90 substantially as specified.

In testimony whereof I affix my signature in presence of two witnesses.

SAMUEL W. BARR.
